Primary Examiner — Jack Reickel*Assistant Examiner* — Salamah Jordan(74) *Attorney, Agent, or Firm* — Polson Intellectual Property Law P.C.; Margaret Polson**(57) CLAIM**

The ornamental design for part of a training apparatus as shown and described.

DESCRIPTION

FIG. 1 is an isometric view of part of a training apparatus.

FIG. 2 is a front side elevation view thereof.

FIG. 3 is a back side elevation view thereof.

FIG. 4 is a right side elevation view thereof.

FIG. 5 is a left side elevation view thereof.

FIG. 6 is a top view thereof.

FIG. 7 is a bottom view thereof; and,

FIG. 8 is an isometric view of the part on a training apparatus.

The features shown in broken lines in the drawings depict environmental subject matter only, and form no part of the claimed designs.

1 Claim, 6 Drawing Sheets(56)
